UNITED STATES PATENT OFFICE.

HUGO HEYMAN, OF GOTTFENBORG, SWEDEN

THREADING-MACHINE FOR CARPET-LOOMS.

No. 902,229.

Specification of Letters Patent.

Patented Oct. 27, 1908.

Application filed June 11, 1904. Serial No. 212,101.

To all whom it may concern:

Be it known that I, HUGO HEYMAN, a subject of the King of Sweden, residing at Gottenborg, Sweden, have invented a certain new and useful Improvement in Threading-Machines for Carpet-Looms, of which the following is a specification.

The present invention relates to improvements in machines for threading the tufts of tuft-yarn spools used in carpet-looms through the tubes on the spool-frame, and is especially applicable for looms for weaving moquette or Royal-Axminster carpets, such for illustration as the type of loom disclosed in the British patent to Tompkinson & Adams, No. 22,604, of 1898. Heretofore the tuft-yarns have been threaded from the spool through the tubes by hand or by machines which have been complicated and generally unsatisfactory. It is the object of the present invention to produce a machine which will be simple and comparatively cheap to manufacture and which will very expeditiously and automatically insert the ends of the tuft-yarns into the tubes.

I attain these objects by the mechanism illustrated in the accompanying drawings, in which, Figure 1 is a front elevation of the machine. Fig. 2 is a plan view. Fig. 3 is a section of the complete machine, taken on the lines 3—3 of Fig. 2. Fig. 4 is a perspective view of parts of the machine. Fig. 5 is a side view of the carriage propelling gear. Fig. 6 is a plan view of a portion of the apparatus with the spool and tube-frame removed. Fig. 7 is a section on the line 7—7 of Fig. 6; and Fig. 8 is a plan view of a portion of the stop mechanism showing the loose pulley in section.

In all of the views like parts are indicated by the same reference characters.

The device comprises a frame upon which slides a carriage, which supports the spool and tube-frame, and a brush, which holds the tuft-yarns distended, and in position to be successively grasped by a hooked needle and drawn down through the tubes. The needle reciprocates in a vertical direction, and passes through a tube, engages with a yarn, which is moved across its path by suitable mechanism, and is drawn down within the tube.

The tuft-yarn spool 1 and the frame 2 are supported upon a carriage 3. This carriage slides upon the rails 4, 5. The spool and

frame 2 are of the usual construction and the details of their construction and configuration depend entirely upon the kind of loom used. The spool is shown rather shorter than is customary so that for the purpose of clearness of illustration a larger scale may be employed. A brush 6, which is a little longer than the length of the spool, is so arranged on the carriage that it will hold the ends of the tuft-yarns distended horizontally from the spool. A strip of wood 7 is arranged so as to press the yarns upon the brush thereby serving the purpose of a guide or clamp to hold the free ends of the tuft-yarns separate and in proper order, the strip of wood 7 serving as a clamping part removably connected thereto and adapted, when in place, to fit over the spaces between the bristles of the brush and clamp the yarns separated and in proper order. This wooden strip is shown as supported upon arms 7', hinged at 7". 7" is a wheel adapted to engage with the rail 4 to press down the strip 7 as is clearly shown in Fig. 3. The spool is supported within the holder 8 by the engagement of its axle 1' with a slit 8' and is provided with a ratchet wheel 9 which engages with a pawl 10 mounted on the carriage so that it cannot be rotated except in the direction to wind up the yarn. The tubes 11 are supported by the frame 2 in the usual manner and are kept in proper alignment by a comb-shaped piece of metal 12, provided with notches, which engage with and separate the tubes. The comb 12 is rigidly secured to the carriage 3. The tubes 11 are removably carried by the frame 2 so that the spool and tubes may be removed from the machine and placed in the loom without disturbing the yarns after they have been threaded through the tubes.

It will be noticed in this machine that the tubes 11 are not round but oval-shaped and are closely connected together. This makes it necessary to arrange the needle so that its longest cross section will be parallel to the tuft-yarns when the latter are stretched between the spool and the brush. The needle cannot therefore turn to engage with the yarns. It is, therefore, necessary in the threading of the tubes to first bring the yarn against the needle and then bring the yarn around it under the hook, so that the hook will engage with the bight of the yarn and draw it downward.

The carriage 3 is adapted to travel from left to right and vice versa on the rails 4, 5, by mechanism about to be described.

The thread needle 13 is carried upon a slide 14 which travels in ways 14' and is operated by an arrangement of levers 15, 16 and 17, the latter being engaged by an eccentric 18 which is mounted upon a shaft 19, the lever 15 being pivoted at 15'. The 10 needle is adapted to be moved upward and downward through whichever tube 11 is at the time being above it. It will there receive the thread and will draw the latter down through the tube. A finger 20 carried by a lever 21 is arranged to pull the thread from the needle by the downward movement of the latter after it has passed downward through the tube, such lever being actuated by engagement with the lever 15. 15

20 In operation the carriage is placed in position at the extreme left side of the machine and is intermittently moved to the right so as to bring the tube successively over the needle which is alternately elevated and depressed passing successively through the different tubes, engaging with the tuft yarn which is above the tube and drawing it down through the tube. The yarn becomes disengaged from the needle by engagement 25 with the lever 20.

The movement of the carriage which serves to place the tubes successively over the needle is made by means of a dog 22 carrying the oppositely arranged beveled ratchets 23, 24, which act on the notches 25, 26, on a rack 27, which is fixed to the frame of the carriage. A projection 28 on the cam 29, which is supported upon the shaft 19, is so arranged as to engage with a friction roller 29' on the dog 22 and elevate it when the needle is in the lowermost position, as shown in Fig. 3. This will cause the pawl 24 to act upon one of the lowermost teeth 26. When the dog 22 is lowered the upper pawl 40 23 engages with a new notch 25, and this is kept up so long as the shaft 19 is rotated successively and intermittently moves the rack 27 to the right and with it the carriage. 45

Supported upon the frame of the machine 50 is a supplemental carriage 31 which is arranged to separate the threads one by one, or when occasion demands it, two by two, and pull the separated thread to one side so that it will be engaged by the needle as the 55 latter descends. To secure this result, the tuft threads which have been previously stretched between the brush 6 and spool 1 enter between the beveled edge plates 32, 33. The space between these plates is little 60 more than the thickness of one thread so that a thread will not ride over others. This space can be regulated by adjusting the position of the plates by means of the supporting screws 32' and 33'. As an additional means for securing this result, two 65

small supplemental brushes 34 and 35 are provided and these brushes are turned by gear wheels 36 and 37 from the shaft 19, sprocket wheels 38 and 39 and a chain 40 and gear wheels 41 and 42. These brushes 70 will successively engage with the tuft yarns as they are about to enter between the plates 32, 33, and will straighten out any yarns which are not in proper position. The supplemental carriage 31 is mounted in fixed 75 slides 43, 44, so that it may be moved a short distance from right to left and vice versa. This supplemental carriage is so arranged that when it is moved to the left, upon the machine being started, it will engage with 80 the first yarn to the right which will be passed between the plates 32 and 33 and will be engaged between the spring hooks 46 and 47, and a vertical plate 48. As the supplemental carriage 31 moves to the left 85 the hooks will engage with the yarn and moving to the right they will bring it in front of the hook of the needle which at this time is elevated. It will be noticed that the hook of the needle is turned toward the 90 brushes. The thread will first engage with a pin 49 carried by the slide 43 so that the thread will not get upon the wrong side of the needle. As the needle descends its hook engages with the tuft yarn to the right and 95 draws it through the tube. The vertical plate 48 is arranged to be moved up and down. It is mounted in slides 48' on the frame 31 and it is engaged with the cam surfaces 50, 51, cut out from the slides 43, 100 44. So mounted it will be seen that the plate 48 will rise when the carriage 31 is moved to the right. This will cause a finger 52 which is fastened to the plate and which extends outside of the hooks to engage 105 with the thread and push it into a notch 53 cut in the plate 48. Thus it will be seen that the yarn is kept away from the free extremities of the hooks when it is drawn down by the needle and all danger of the yarn engaging with the hooks is avoided. The hooks are secured to the supplemental carriage 31 by a plate 54, which is provided with a securing screw 55 by means of which 110 they may be adjusted. The space between 115 the plate 48 and the points of the hooks should be substantially the thickness of one yarn. If two yarns or more are to be threaded in each tube the space mentioned must be made sufficiently large to permit 120 this being done. This can be regulated by adjusting the hooks by means of the supporting screw 55. The supplemental carriage 31 may be operated in any manner, the means illustrated consisting of an extension of the lever 13, the cord 56 and retracting spring 57. The cord 56 is secured to the rear face of the supplemental carriage and leads over a guide pulley carried at the right hand end of the fixed slideway 43, 125 130

thence over another guide pulley at the rear of the machine 2 to the extension of the lever 15. The spring 57 is secured to the front of the supplemental carriage and to the left hand end of the slideway, 43, so that its tendency will be to hold the carriage to the left side of the slideways until the extension of the lever 15 is depressed by its spring when the carriage will be drawn by 10 the cord 56 to the right hand end of the slideways. The operating means for the supplemental carriage is adjusted to move it to its extreme left hand position when the needle is depressed, and to its extreme right 15 hand position when the needle is elevated.

The shafts of the circular brushes and the slides 43, 44, are held stationary by a support 58, which is fastened to the table 59 of the machine. Upon this table all of the 20 fixed parts of the machine are secured.

As shown in Fig. 3, the dog 22 is provided with a slot 64 which engages with a pin 65 on the table 59, and about which it may pivot, when it is desired to disengage 25 the ratchets from the rack 27. A rod 66 engaging with the slot 67 on the dog holds it in constant engagement with the rack.

Working through a slot 61' in the table 59 is a stop pin 62 by means of which the stop 30 motion is operated. The pin 62 is carried by a shaft 68 which is slidably mounted in bearings 69 secured to the under side of the table, and above the shaft 19 and is held in its extreme left-hand position by a spring 35 68'. On the shaft 19 are mounted a loose pulley 61 and a fast pulley 70, the fast pulley being within the loose pulley.

In one side of the fast pulley 70 is a slot 71 extending the length thereof and working 40 within this slot is a slide 72 of a length somewhat greater than that of the pulley 70. By means of a rib projecting through a narrow slot 73 the slide has secured thereto a cam plate 74 which covers a portion of the face 45 of the pulley 70 and by means of which the slide may be moved to cause its projecting end to project from one side or the other of the fixed pulley.

The cam plate is moved by the arms 75 50 and 76 carried by the sliding shaft 68, as shown in Fig. 8 and these arms are so constructed as to limit the extent of movement of the cam plate.

Secured to one side of the loose pulley 61 55 is an abutment 77 with which the slide 72 engages when it is desired to lock the fast and loose pulleys together and start the machine. The slide may be locked in engagement with the abutment by means of a 60 spring pressed latch 78 pivoted to the side of the loose pulley.

Pivoted in the bearing plate 69 at the side 65 of the pulley 70 opposite to the abutment 77 is a spring actuated brake 79 provided with a notch 80 for engagement with the slide 72,

when the said slide is caused to project from that side of the fast pulley and the machine brought to rest.

Pivoted on top of the table 59 is a lever 63 by means of which the machine 70 may be started by hand. One end of the lever 63 is bifurcated to straddle the stop pin 62.

Pivoted to the top of the table 59 is a spring actuated hook 81 which engages a pin 75 82 on the lever 63 to lock the stop pin in its extreme right hand position when the parts of the clutch are locked together and the machine is in operation. Projecting from the rear end of the hook 81 is a toe 83 which 80 may be engaged by a finger 84 carried on one of the braces 85 of the carriage 3, to tilt the hook 81 away from the pin 82 when the carriage has reached its extreme movement to the right and the last yarn has been drawn through its tube, thus allowing the spring 61' to move the shaft 68, arms 75 and 76 to the left thereby throwing the cam 74 and through it the slide 72 out of engagement with the abutment 77 and into engagement 90 with the brake 79 thus automatically bringing the machine to rest.

The table is provided with stops for limiting the movements of the lever 63 and hook 81, and the hook is provided with a chain, 95 cord or rod by means of which the stop mechanism may be unlocked by hand.

Having now described my invention, what I claim and desire to secure by Letters Patent, is:—

1. In a machine for threading tuft yarns through the frame tubes in carpet looms, the combination with a support for the spool, tubes and a support therefor, of means for supporting the yarn adjacent to the tubes in 105 the path of the needle, a needle, and means for reciprocating the needle successively through the tubes to engage with the yarns and draw them through the tubes.

2. In a machine for threading tuft yarns 110 through the frame tubes in carpet looms, the combination with a support for the spool, tubes and a support therefor, of a brush for supporting the yarns adjacent to the tubes, a needle, and means for reciprocating the 115 needle successively through the tubes to engage with the yarns and draw them through the tubes.

3. In a machine for threading tuft yarns through the frame tubes in carpet looms, the 120 combination with a support for the spool, of tubes and a support therefor, of a brush for supporting the yarns adjacent to the tubes, a needle, means for reciprocating the needle successively through the tubes, and means 125 for engaging the yarns with the needle.

4. In a machine for threading tuft yarns through the frame tubes of carpet looms, the combination with a carriage supporting the 130 spool, tubes and a support therefor, and a

- brush for supporting the yarns adjacent to the tubes, of a needle, and means for reciprocating the needle successively through the tubes to engage with the yarns and draw them through the tubes.
5. In a machine for threading tuft yarns through the frame tubes of carpet looms, the combination with a carriage supporting the spool, tubes and a support therefor, and a brush for supporting the yarn above the tubes, of a needle and means for reciprocating the needle successively through the tubes and means for engaging the yarns with the needle.
10. 6. In a machine for threading tuft yarns through the frame tubes of carpet looms, the combination with a carriage supporting the spool, tubes and a support therefor, and a brush for supporting the yarn above the tubes, of a needle, and means for reciprocating the needle successively through the tubes, and a supplemental carriage having means for engaging the yarn to draw it against the needle.
15. 7. In a machine for threading tuft yarns through the frame tubes of carpet looms, the combination with a carriage supporting the spool, tubes and a support therefor, and a brush for supporting the yarn above the tubes, of a needle and means for reciprocating the needle successively through the tubes, a supplemental carriage having means for engaging the yarn to draw it against the needle, the said supplemental carriage having plates between which the yarn is drawn.
20. 8. In a machine for threading tuft yarns through the frame tubes of carpet looms, the combination with a carriage supporting the spool, tubes and a support therefor, and a brush for supporting the yarn above the tubes, of a needle and means for reciprocating the needle successively through the tubes, a supplemental carriage having means for engaging the yarn to draw it against the needle, the said carriage having hooks for engaging with the yarn.
25. 9. In a machine for threading tuft yarns through the frame tubes of carpet looms, the combination with a carriage supporting the spool, tubes and a support therefor, and a brush for supporting the yarn above the tubes, of a needle and means for reciprocating the needle successively through the tubes, a supplemental carriage having hooks for engaging with the yarn to draw it against the needle, the said carriage having means for freeing the yarn from the hooks.
30. 10. In a machine for threading tuft yarns through the frame tubes of carpet looms, the combination with a carriage supporting the spool, tubes and a support therefor, and a brush for supporting the yarn above the tubes, of a needle and means for reciprocating the needle successively through the tubes, of means for successively moving the carriage, and means for engaging the yarn to draw it against the needle.
35. 11. In a machine for threading tuft yarns through the frame tubes of carpet looms, the combination with a carriage supporting the spool, tubes and a support therefor, and a brush for supporting the yarn above the tubes, of a needle and means for reciprocating the needle successively through the tubes, of means for successively moving the carriage, and a supplemental carriage carrying means for engaging the yarn to draw it against the needle.
40. 12. In a machine for threading tuft yarns through the frame tubes of carpet looms, the combination with a carriage supporting the spool, tubes and a support therefor, and a brush for supporting the yarn above the tubes, of a needle and means for reciprocating the needle successively through the tubes, of means for successively moving the carriage, and a supplemental carriage carrying hooks for engaging the yarn to draw it against the needle, and means for disengaging the yarn from the hooks.
45. 13. In a machine for threading tuft yarns through the frame tubes in carpet looms, the combination with a support for the spool, tubes and a support therefor, of means for supporting the yarns adjacent to the tubes, and means for engaging and successively drawing the yarns through the tubes.
50. 14. In combination in apparatus of the class described, a guide or clamp to hold the free ends of the tuft threads separate and in proper order, and means for threading the said threads through the guide tubes of the spool frame, substantially as described.
55. 15. An alining guide for holding the free ends of the tuft yarns in carpet manufacture, said guide comprising means for clamping the yarns separated and in proper order, substantially as described.

This specification signed and witnessed
